UNITED STATES PATENT OFFICE

1,986,131

LIQUID FUEL BURNER

Carl E. Anderson, Brockton, Mass.

Application July 30, 1934, Serial No. 737,636

8 Claims. (Cl. 158—92)

This invention relates to improvements in liquid fuel burners and particularly one of the heater type, although adaptable to other installations.

5 The use of fuel oil for heating has rapidly become more extensive and many devices have been placed on the market attempting to overcome certain difficulties which have limited the wider acceptance of liquid fuel in spite of its many conveniences. The most serious of these difficulties is the need of reducing the fuel consumption and the noise of combustion of the burner in operation.

10 My present invention has for its main object the provision of a liquid fuel burner that is extremely economical in operation regardless of the grade of fuel oil used. While economy in such a burner is best evidenced by the reduction of fuel consumption, it is also well represented by other 15 advantages which my invention affords, such as, freedom from carbonization and quietness of operation, permitting safe and efficient use.

20 I am able to effect these economies by providing a burner in which the fuel will be thoroughly vaporized and mixed with air and water vapor and thoroughly burned with the heat of combustion evenly distributed upwardly and outwardly as a flaring sheet of flame.

25 I am aware of the fact that attempts have been made to utilize a steam generator to vaporize the fuel, but none of which I am aware succeed in effectively carrying out the advancement to the art I am able to achieve.

30 My invention is capable of installation in any fire box and, of course, standard ignition and control equipment may be used. These have, however, been omitted from the drawing and specification in which I have shown and described a simple embodiment of my invention 35 showing only such controls as are necessary for absolute safety.

In the drawing:

40 Fig. 1 is a partly sectioned view of a burner constructed in accordance with my invention installed in a suggested fire box, and

45 Fig. 2 is a partly sectioned fragmentary plan view of the supply pipes and safety controls on the exterior of the furnace.

50 An oil burner constructed in accordance with my invention may be easily installed in any fire box 1 as it is supported by a base 2 through which are threaded the adjustable legs 3 to permit proper levelling of the unit on the furnace floor 4. The space between the top of the burner 55 and the wall of the fire box is preferably sealed as by the plate 5 anchored in or to the wall 6 of the fire box 1 as at 7 and preferably made tight with asbestos or like cement as indicated at 8.

60 The base 2 is provided with an upright 9 onto

which the bowl B is threaded. The bowl consists of a heavier bottom member 10 and a relatively thin, lighter side wall 11 which is secured to the mouth 10^a of the member 10 which has an external flange 12 for that purpose. A rim plate 13 overhangs the open end of the wall 11 and contacts the plate 5.

65 The upper portion 14 of the upright 9 is formed as a fitting and extends within the bowl B. The portion or pipe 14 is plugged as at 15 and is provided with radial jets 14^a. The axial fuel feed 14 is connected to the fuel inlet pipe 16.

70 The delivery end of the pipe 14 is surrounded by the axial core 17 which is mounted on the annular shoulder 18 on the member 10. The core 17 is provided with a plurality of apertures 19 in its lower portion to permit the passage of the oil into the bowl 10 where it is vaporized. The core 17 serves also as a support for the baffle plate 20 which substantially overhangs the 75 space between the core 17 and the rim plate 13. The baffle plate 20 may be provided with apertures 20^a as needed to provide the proper flame trend.

75 The member 10 is provided with a row of air inlets 10^b disposed just below the flange 12 and the wall 11 is provided with three rows of air inlets 11^a. The number and arrangement of these intake apertures may, of course, be varied if necessary to suit varying conditions.

80 The wall 11, the core 17, and the baffle plate 20 are preferably made of chromium steel.

85 Surrounding the core 17 is a vaporizing coil 21 fed by a water inlet 22. The upper portion of the coil pipe 21 is provided with vents 23 on the lower side of the pipe 21 and are spaced along the pipe 21 until the core 17 is encircled with steam vents. They are preferably disposed to discharge downwardly and outwardly into the 90 concavity of the bowl 10. The bowl 10 has its interior dished or curved. It may be spherical or oblate, or, in fact, any desired figure of revolution providing for the proper impingement of the steam and its return upward to give upward 95 draft for the vaporized oil.

100 I provide an overflow drain pipe 24 from the member 10 to a bucket 25. The water line 22 from any suitable source as a water main fed either by gravity or pressure is provided with a weight valve indicated at 26 adapted for use with a thermostatic controlled system and a manually operated valve 27 and it may also be filtered if necessary. In order that only a predetermined maximum of water be used, a jetted plug 28 is 105 threaded into the pipe 22. The equipment needed will vary considerably with the particular service to be rendered. While the feed is preferably delivered at about ten pounds pressure 110 for furnace use, satisfactory results, particularly 115

with small heaters, may be obtained with fuel fed by gravity.

The oil pipe 16 may come from a pressure tank or like source. Neither tank nor pump is shown as standard equipment is available. The oil is delivered at about ten pounds pressure and the line is controlled by a weight valve 26^a and a manually operated valve indicated at 27^a and the flow is controlled by a jettied plug 28^a so that the possibility of flooding the burner is decreased.

A second valve 29 in the oil pipe 16 is controlled by the lever 30, one end of which is normally depressed by the weights 31 to keep the valve 29 open. The other end of the lever carries the bucket 25 and is adapted to be tilted by drainage.

I provide a standard trip valve indicated as at 29^a to be released by downward movement of the lever 30 so that the water pipe 22 will be also closed.

At 32 I have indicated a fusible valve so that the oil pipe 16 will be automatically closed in case of fire.

In operation, the oil is first turned on and the fuel oil ignited. After a short interval the water is then opened up and steam is generated. This effectively vaporizes the oil and carries the mixture upwardly and outwardly to where an adequate supply of air is available for perfect combustion. The rim plate 13 tends to throw the flame against the baffle plate 20 which spreads the flame to cover the maximum area. Proper adjustment of the valves permits the proper mixtures of water and fuel oil.

It will be noted that the flame is so controlled that only the baffle plate 20 is subjected to intense heat for the flame is directed away from the core 17 by the steam and from the walls 10 by the inward and upward air draft.

Thus, I am able to burn thoroughly the oil after vaporization and provide a structure which protects itself from carbonization and with the protection afforded by the valves my invention permits oil burners extremely safe and efficient.

What I therefore claim and desire to secure by Letters Patent is:

1. In a liquid fuel burner, a bowl, the upper part of said bowl being formed with a plurality of air inlets, a lip overhanging the interior edge of said bowl, an axial oil inlet in said bowl, a baffle plate, a core surrounding said inlet and supporting said baffle plate above the open end of said bowl, said core having apertures in its lower portion and a water vaporizing coil surrounding said core having downwardly disposed steam vents whereby the vaporized fuel is carried upwardly and outwardly towards said air inlets and the flame directed towards said baffle plate.

2. In a liquid fuel burner, a bowl, the upper portion of said bowl being provided with a plurality of air inlets and constituting a combustion chamber, the lower portion of said bowl constituting a vaporizing chamber, an oil inlet axially entrant of said vaporizing chamber, an axially disposed steam generator having vents disposed to discharge steam towards the bottom of said bowl to vaporize said oil and to carry said vaporized oil outwardly and upwardly into said combustion chamber.

3. In a liquid fuel burner, a bowl, the upper portion of said bowl being provided with a plurality of radial air inlets and constituting a combustion chamber, the lower portion of said bowl

constituting a vaporizing chamber, an oil inlet axially entrant of said vaporizing chamber, an axially disposed steam generator having vents disposed to discharge vapor towards the bottom of said bowl to scavenge said oil and to carry said oil outwardly and upwardly into said combustion chamber, and an overflow drain in said vaporizing chamber.

4. In a liquid fuel burner, a bowl, the upper portion of said bowl having a plurality of radial air inlets and constituting a combustion chamber, the lower portion of said bowl constituting a vaporizing chamber, an oil inlet axially entrant of said vaporizing chamber, an axially disposed steam generator having vents disposed to discharge vapor towards the bottom of said bowl to vaporize said oil and to carry said vaporized oil outwardly and upwardly into said combustion chamber and a water inlet to said generator, said oil inlet and said water inlet having restricted passages to limit the maximum flow of fluids, and means for controlling the flow of the fluids.

5. In a liquid fuel hydrocarbon burner to be installed in a fire box, a bowl, a cylindrical shell thereon having air inlets, an oil feed disposed axially of the bowl, a steam generator spirally disposed about the oil feed axis and having vents disposed to impinge water vapor upon said bowl below said air inlets to create an interior radial flow of the vaporized fuel upward of the bowl axis, baffle plates for the burner comprising a central baffle plate for the open end of said shell, and an annular plate overlying the shell edge and positioned substantially to seal the shell to said fire box.

6. In a liquid fuel burner to be installed in a fire box, a bowl of substantially hemispherical figure, a cylindrical shell thereon having radial air inlets in its upper portion, a central cylindrical axial core, an oil feed disposed axially of the bowl, a steam generator spirally disposed about the oil feed axis and having vents disposed to impinge water vapor upon said bowl below said air inlets to create an interior radial flow of vaporized fuel upward of the bowl axis, baffle plates for the burner comprising a central baffle plate for the open end of said shell supported by said core, and an annular plate overlying the shell edge and positioned substantially to seal the shell to said fire box.

7. In a liquid fuel burner, a fire box, the upper part of said box being provided with a plurality of air inlets and constituting a combustion chamber, the lower part of said box constituting a vaporizing chamber, an oil inlet centrally disposed in said vaporizing chamber and a steam generator having vents disposed to discharge steam towards the bottom of said box to vaporize said oil and to carry said vaporized oil outwardly and upwardly into said combustion chamber.

8. In a liquid fuel burner, a fire box, the upper part of said box being provided with a plurality of air inlets, the lower part of said box constituting a vaporizing chamber, an oil inlet centrally disposed in said vaporizing chamber, a steam generator having vents disposed to discharge steam towards the bottom of said box to vaporize said oil and to carry said vaporized oil outwardly and upwardly into said combustion chamber, said air inlets in said combustion chamber being disposed about said combustion chamber and being of a size depending on the distance thereof from the oil inlet axis sufficient to secure thorough combustion of said vaporized oil.

CARL E. ANDERSON.
